Primary Examiner — Angela J Lee*Assistant Examiner* — Liv C Anderson(74) *Attorney, Agent, or Firm* — Renaissance IP Law Group LLP(57) **CLAIM**

The ornamental design for a dental dual light, as shown and described.

DESCRIPTION

FIG. 1 is a perspective view showing our new design for a dental dual light;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The portions shown in broken lines illustrate environmental structure and form no part of the claimed design.

1 Claim, 7 Drawing Sheets(56)
